CLAIM

The ornamental design for a grill brush, as shown and described.

DESCRIPTION

FIG. 1 is perspective view showing the top, front and right side of a grill brush embodying my new design, the portion in broken lines forming no part of the inventive design; FIG. 2 is an enlarged right side elevational view thereof, the left side being a mirror image thereof; FIG. 3 is a rear elevational view thereof; FIG. 4 is an enlarged, front elevational view thereof; and, FIG. 5 is a bottom plan view thereof.
